(57) **CLAIM**

The ornamental design for a programmable controller as shown and described.

DESCRIPTION

FIG. 1. is a perspective view of the front, right, and top sides of a programmable controller showing our new design; FIG. 2. is a perspective view of the rear, left, and bottom sides thereof;

FIG. 3. is a front view thereof;

FIG. 4. is a rear view thereof;

FIG. 5. is a top plan view thereof;

FIG. 6. is a bottom view thereof;

FIG. 7. is a right side view thereof; and,

FIG. 8. is a left side view thereof.

The broken lines shown represent portions of the programmable controller and form no part of the claimed design.

1 Claim, 8 Drawing Sheets
